UNITED STATES PATENT OFFICE.

WILLIAM BAXTER, JR., OF NEWARK, NEW JERSEY.

IMPROVEMENT IN COMPOUND ENGINES.

Specification forming part of Letters Patent No. **153,300**, dated July 21, 1874; application filed February 18, 1874.

To all whom it may concern:

Be it known that I, WILLIAM BAXTER, Jr., of the city of Newark, in the county of Essex and State of New Jersey, have invented certain Improvements in Compound Engines, of which the following is a specification:

This invention relates to engines in which the steam, after it has performed its duty in one or more cylinders, is exhausted into a cylinder of larger capacity, where it continues its duty, subject to expansion, and may be ultimately passed to a condenser, to give the piston of the larger cylinder the advantage of a vacuum.

The improvements are fully hereinafter described and claimed.

In the accompanying drawing, Figures 1 and 2 represent, mainly, central vertical sections, in planes at right angles to each other, of a compound engine constructed in accordance with the invention. Fig. 3 is a horizontal section upon a larger scale, mainly as indicated by the line $x x$ of the cylinders, valve-chest, and certain of the passages.

Similar letters of reference indicate corresponding parts.

In the particular application of the invention shown in the drawings, the engine-cylinders are represented as occupying an overhead position; but this may be reversed, or, instead of the engine being vertical, it may occupy a horizontal or inclined position.

A A' are the two high-pressure cylinders disposed one on either side of the low-pressure cylinder B, all of which may be steam-jacketed. C C' and D are the pistons of said cylinders. The pistons C C' of the smaller and outside or high-pressure cylinders A A' are connected by their rods $a a'$ with the ends of a sliding cross-head, E, which works up and down within guides F F on opposite sides of the main frame. The piston D of the intermediate and larger or low-pressure cylinder B is connected, by its rod b , with the same cross-head E at its center.

Inasmuch as the cylinders A A' are of the same diameter, and their pistons exposed to equal pressures, there is no tendency of the cross-head to tip or tilt at its ends, and it is stiffened or steadied at its center by the connection therewith of the intermediate or larger

piston D. This gives a very firm and effective action, and divides the strain over the cross-head.

Rotary motion is communicated to the engine-shaft G from the cross-head E by pitman H and wrist-pin d . While the pistons of the three cylinders A A' B are each made to communicate their respective forces to the cross-head E, the power exerted by the pistons C C' is more directly applied, as it were, to working the feed-pump I and air-pump J of the engine by the extension of the piston-rods $a a'$ below or beyond the cross-head. This, too, forms a very compact, simple, and effective combination. K is the valve-chest, which is common to all the cylinders, and contains a single valve, which may either be a straight sliding valve, or a curvilinearly-vibrating one, but which is constructed substantially as follows, to control the admission and delivery to and from all the cylinders. Thus, said valve L is of a double-**D** shape—that is, one **D** outside of the other; or, in other words, is formed with an inner-face cavity, e , and an outer passage, f , which latter also opens at its ends in or through the face of the valve. Such valve is of a width and length to control the following ports and passages, viz: Ports and passages $g g$ leading from the valve seat or face to the upper ends of the cylinders A A'; similar ports or passages $g' g'$ leading to the lower ends of said cylinders; also, a central exhaust-port, h , which may lead to the condenser; and ports and passages $i i'$ connecting the valve-chest or valve-seat with the upper and lower ends of the low-pressure cylinder B. When the valve is shifted to allow steam from the valve-chest to pass either one end of the valve and enter, by the one set of passages, $g g$ or $g' g'$, the upper or lower ends of the cylinders A A', such motion brings the outer passage f in the valve in communication with the other set of said passages $g g$ or $g' g'$, and passes the spent steam in the cylinders A A' from the opposite sides of the pistons therein, by one of the passages i or i' , to the cylinder B, while the other of said passages i or i' is put in communication, by the cavity e and exhaust-passage h , with the condenser, or with the atmosphere, the exhaust steam from the cylinders A A' acting simultaneously on the piston D with

the live steam from the valve-chest on the pistons C C', and the pressure being on corresponding faces of all the pistons to reciprocate them in common.

The requisite motion may be communicated to the valve L by an eccentric, l, on the main shaft, made to rock a shaft, m, which in its turn, by crank or arms and connecting-rod, rocks a way-shaft, n, that, by a further crank or arm, o, and rod r, reciprocates the valve, as required. Furthermore, the rod connecting the rock-shaft n with the rock-shaft m may be connected with the latter by a reversing-slide similar in its action to the link motion in other

valve-gears for reversing or stopping the action of the engine.

I claim—

The low-pressure cylinder B, having the slide-valve L with its ports, as shown, and piston D with its rod b connected to the cross-head E, in combination with the high-pressure cylinders A A', their rods a a', air-pump J, and feed-pump I, all constructed and arranged substantially as described, for the purpose specified.
